DESCRIPTION

U.S. PATENT DOCUMENTS

FIG. 1 is a front view of a display screen or portion thereof with a graphical user interface showing our new design; and, FIG. 2 is a front view of a display screen or portion thereof with a graphical user interface in accordance with a second embodiment.

4,960,128 A 10/1990 Gordon et al.
4,964,408 A 10/1990 Hink et al.

The broken lines, including those showing a display screen or portion thereof and those depicting portions of a graphical user interface, form no part of the claimed design.
